DESIGN FOR A TELEPHONE-ADDRESS INDEX OR SIMILAR ARTICLE

Garfield L. Beckstrom, Chicago, Ill., assignor to Autopoint Company, Chicago, Ill., a corporation of Illinois

Application July 2, 1946, Serial No. 131,256

Term of patent 14 years

(Cl. D74—1)

To all whom it may concern:

Be it known that I, Garfield L. Beckstrom, a citizen of the United States, residing at Chicago, in the county of Cook and State of Illinois, have invented a new, original, and ornamental Design for a Telephone-Address Index or Similar Article, of which the following is a specification, reference being had to the accompanying drawing, forming a part thereof.

In the drawing:

dress index or similar article, embodying my new design;

Fig. 2 is a view in side elevation of the same;
Fig. 3 is a view in front elevation of the same;
and

Fig. 4 is a view in rear elevation thereof.

I claim:

The ornamental design for a telephone-address index or similar article, substantially as shown.
